(57) **CLAIM**

The ornamental design for a belt guard, as shown and described.

DESCRIPTION

FIG. 1 is a front elevation view of a belt guard showing the new design;

FIG. 2 is a back elevation view thereof;

FIG. 3 is a top plan view thereof;

FIG. 4 is a bottom plan view thereof;

FIG. 5 is a left-side view thereof;

FIG. 6 is a right-side view thereof;

FIG. 7 is a perspective view thereof; and,

FIG. 8 is an enlarged view of the encircled portion in FIG.

1.

The dashed lines in FIG. 1 and FIG. 8 represent boundary lines and form no part of the claimed design.

1 Claim, 8 Drawing Sheets
